UNITED STATES PATENT OFFICE

2,575,385

DRIVE FOR TRAVERSE MECHANISM

Joseph L. Killoran, Drummondville, Quebec,
Canada, assignor to Celanese Corporation of
America, a corporation of Delaware

Application July 4, 1945, Serial No. 603,157

19 Claims. (CL 242—43.3)

1

This invention relates to traverse mechanisms for textile machines, and relates more particularly to hydraulic drives for traverse mechanisms for use in connection with the yarn winding devices on spinning machines.

In drives for traverse mechanisms of the type heretofore employed, the use of traverse cams and drives therefor presented many mechanical difficulties making for a continual source of trouble. Another factor which contributed to lower considerably the efficiency of prior traverse mechanisms was the produced defects in the build of the yarn package due to the inherent troubles resulting from the cam driven traverse.

It is an object of this invention to provide an improved traverse mechanism for textile machines which will be free from the foregoing and other disadvantages and which will be especially simple in construction and efficient in operation.

Another object of this invention is the provision of a traverse mechanism for a textile machine wherein traverse cams and traverse drives are eliminated and the defects in the build of the yarn package due to the use of traverse cams are avoided.

A further object of this invention is the provision of a hydraulic traverse mechanism for a yarn spinning machine which causes the traverse bar to move with a reciprocating motion at a uniform speed.

Still another object of this invention is to provide an improved traverse mechanism for a textile machine for producing yarn packages of superior construction.

Other objects and advantages of this invention, together with certain details of construction and combinations of parts, will appear from the following detailed description and drawings.

In the drawings wherein a preferred embodiment of this invention is shown,

Figure 1 is a partial front elevational view of a spinning machine showing the hydraulic traverse mechanism of this invention operatively connected thereto.

Figure 2 is a front elevational view of the hydraulic traverse mechanism per se.

Figure 3 is a perspective view of the rear of the hydraulic traverse mechanism, on a slightly smaller scale.

Figure 4 is a cross-sectional view, on an enlarged scale, of the cylinder and valve structures of the traverse mechanism.

Figure 5 is a side-elevational view of the traverse mechanism.

2

Figure 6 is a cross-sectional detail view of the mechanism for providing a superimposed traverse or "creeping" motion, and

Figure 7 is a cross-sectional view taken on line 5 1—1 of Figure 2.

Similar characters of reference indicate similar parts throughout the several views of the drawings.

In its broadest aspect the present invention 10 comprises a traverse mechanism providing a reciprocating motion at uniform speed by means of a double acting hydraulic cylinder with a piston driven by hydraulic pressure. Uniform speed of motion is assured by using a positive displacement type liquid pump rotating at constant speed. The volume of liquid passing through the pump and cylinder is practically independent of pressure fluctuation, permitting the piston to move at a uniform speed. The constant flow of liquid assures the instantaneous reversal of the piston when the flow of liquid to the cylinder is reversed.

Referring to the drawings for a detailed description of my novel traverse mechanism, the reference numeral 8 indicates generally a spinning unit which comprises a plurality of spinning chambers or cells 9, a single spinning unit being made up of up to 50, 100 or even more cells. The bundles of freshly spun filaments issuing from the cells 9 are twisted and wound upon suitable bobbins or other yarn supports by a ring spinning and winding arrangement generally indicated by reference numeral 11. The twisting and winding arrangement includes reciprocating ring rails 12 and 13 which are operated by my novel traverse mechanism generally indicated by reference numeral 14. The traverse mechanism is supported by a transverse beam 15 of the spinning unit, being attached thereto by bolts 16.

The drive of the traverse mechanism comprises a double-acting oil cylinder 17 containing a piston 18 to which is fixed a piston rod 19. The piston rod extends through glands 21 at both ends of the cylinder and each extension is provided with a rack 22. The racked portion of the extension is carried in a cylindrical bearing member 23 for reciprocation therein. In connection with each bearing member 23 there is provided a housing 24. In each housing 23, there is journaled a cross-shaft 25, 25' on which is fixed a spur gear 26 adapted to mesh with and be rotated by rack 22. Externally of housings 24, there is fixed to each cross-shaft 25, 25' an eccentric roller chain sprocket 27, the purpose of 50 which will be set forth hereinafter.

A pneumatically operated cylindrical quick acting valve, generally indicated by reference numeral 28, is provided to effect instantaneous reversal of the flow of oil operating the piston 18 of the oil cylinder 14. The valve casing is provided with integral brackets 29 adapted to be attached by means of bolts 31 to bosses 32 integral with the casing of oil cylinder 14 so as to support the reversing valve therefrom. The reversing valve 28 is provided with a piston 33 having annular projections 34 thereon for selectively closing ports 35 in the casing of the reversing valve thus controlling the flow of oil to the oil cylinder 14 through conduits 36 connected to the ports and to the end walls of the oil cylinder.

Piston 33 is reciprocated in the reversing valve cylinder 28 by air pressure controlled by a suitable valve, generally indicated by reference numeral 37, operated by the rotation of cross-shaft 25'. The air valve 37 is provided with an inlet 38 connected to a suitable supply (not shown) of compressed air, an air exhaust 39, a pipe connection 41 to one end of the reversing valve 28 and a pipe connection 42 to the other end of the reversing valve. The air valve 37 is so arranged to operate through rack 22, spur gear 26 and cross-shaft 25 that as the piston 18 in cylinder 14 nears the end of its stroke air pressure is loaded at one end of piston 33 of reversing valve 28. At the end of stroke of piston 18, the rack 22 at the other end of piston rod 18 operates a cam 43 fixed to cross-shaft 25 for tripping a latching mechanism, generally indicated by reference numeral 44, through means including a bar 45 passing through suitable openings 46 in brackets 29. The tripping of the latching mechanism 44 permits the piston 33 to move to the other end of the cylinder of the reversing valve 28 at which point it is again latched, thus opening the port 35, which was closed, to one conduit 36 and closing the other port 35 which was open, the latter port being operatively connected in this position of the piston 33 to oil exhaust pipe 47 which returns the oil to oil supply tank 48.

The oil supplied to valve 28 and thence to cylinder 14 is furnished by tank 48 through pipe 49 in which is provided a valve 51. The oil is supplied to a positive displacement type oil pump 52, which may be driven from a spinning machine element so that any change in the speed of the machine may produce a corresponding change in the speed of the traverse or, as shown, it may be operated by a motor 53, which feeds the oil under suitable pressure through pipe 54, having a fluid pressure gauge 55 therein, to branched pipe 56 for selectively supplying oil under pressure to the desired port 35. The use of a positive displacement type of oil pump rotating at constant speed assures uniform speed of motion. The volume of oil passing through the pump and cylinder is practically independent of pressure fluctuations. Therefore, the piston moves at a uniform speed. This constant flow of oil also assures substantially instantaneous reversal of the piston when the flow of oil to the cylinder is reversed. Any oil seeping past annular bearing members 57 integral with piston 33 is removed through ports 58, coupling 59 and tubing 61 to a suitable drain (not shown). Stop cocks 62 are provided at each end of cylinder 14 to bleed any air contained therein.

The latching and tripping mechanisms comprise dogs 63, 63' which are pivoted on pins 64 fixed in the walls of cylinder 33 and have a portion extending into opening 64' in piston 33. The

dogs are pulled toward each other by means of a contractile spring 65 mounted in apertures 66 in the heads of said dogs. The dogs are latched separately, i. e. when one is latched, the other is unlatched. The latching is effected by means of bell-crank levers 67, 67' pivotally mounted on pins 68 carried by brackets 69 mounted on cylinder. The lower or horizontal branch of the bell-crank levers are bifurcated to receive the head of dog 63, and the extremity of each of said lower branches has journaled therein a roller bearing 71. The bell-crank levers 67, 67' are spring loaded, a contractile spring 72 being connected to the extremity of each of the vertical branches of the bell-crank levers and to cylinder 14. The springs 72 are adapted to force the lower branch of the levers 67, 67' into latching position. The vertical branches of the bell-crank levers are provided with adjustable bolts 73 for cooperating with projections 74 on brackets 69 and projections 75 on rod 45.

The rod 45 is connected to a connecting bar 75 through a free-wheeling device generally indicated by reference numeral 76 (see Figures 2 and 6). The connecting bar 75' passes through a suitable passage in a guide bracket 77 mounted on one of the bearing members 23, and the free-end of said connecting bar is provided with a roller bearing 78 adapted to receive the thrust 30 of projections 79 on cam 43 during the tripping operation of the latching mechanism.

The free-wheeling device 76 provides a very small superimposed traverse or creeping motion on the main traverse. This is effected by means 35 of an eccentric sleeve 81 on which is mounted a housing 82 having fixed thereto a link 83. A connecting link 84 is pivotally attached at one end thereof to link 83 and at the other end thereof to cam 43. The connecting bar 75' is pivotally attached to a housing 85 which is mounted on and covers a ball race 86 on the eccentric sleeve 81. A cover 87 is screw-threaded on housing 82. The eccentric sleeve 81 is rotated, with a ratchet-like motion and with no back drive, a small amount on each stroke of the main piston 49. The amount of rotation of the eccentric sleeve is adjustable by adjusting the position of connecting link 84 along the length of link 83.

On each of sprockets 27 is attached one end 50 of a roller chain 88, the other end of said roller chain being attached to a horizontally reciprocating rod 89. Also attached to said rod 89 is one end of a roller chain 91 which is trained over an idler sprocket 92, the lower end of said roller chain 91 being suitably fixed to the lower extremity of a lifter rod 93 mounted for vertical reciprocation in a lifter rod bracket 94. As shown in Figure 1, two traversing ring rails 12 and 13 are provided, each operating with respect to one-half of the bobbins 95 on the spindle bank. The sprockets 27 are arranged to pull in opposite directions, each driving one traversing ring rail, thus providing a balanced traverse, that is, the traversing ring rail on one half of the spinning unit is going up while the other is going down. In Figure 1, the left hand sprocket 27 is shown with rod 89 pulled toward the left, thus operating the lifter rods 93 on that side of the unit to push upwardly the traversing ring rail 12 and to cause traversing ring rail 13 to be lowered.

The eccentricity of sprockets 27 provides a uniform accelerated rate of traverse to the ring rails thus producing the desired taper of the package of yarn being wound. While my novel drive for the traverse mechanism is designed to obtain as

close as possible instantaneous reversal at the end of the stroke, it will be realized that absolute instantaneous reversal is a physical impossibility; a slight amount of deceleration and acceleration occurs at the end of the stroke giving rise to a slight accumulation of yarn at the end of the bobbins. This is spread out by the free-wheeling device above described which superimposes a miniature slow speed traverse on top of the main traverse, in other words by setting the main traverse very slightly shorter than the actual traverse between the flanges of the bobbins and then gradually shifting it up and down to the extent of the difference.

While balancing the drive of this invention by having half of the traverse rising while the other half is lowering is advantageous, it will be appreciated that one of the drive sprockets 27 may be omitted entirely and the whole device driven from the other drive sprocket. Moreover, although uniformly accelerated traverse speed is provided by means of the eccentric drive sprocket as shown, a uniform traverse speed, which will traverse a straight parallel cylindrical package instead of a tapered package, may be provided simply by replacing the eccentric sprocket by an ordinary concentric sprocket.

It is to be understood that the foregoing detailed description is given merely by way of illustration and that many variations may be made therein without departing from the spirit of my invention.

Having described my invention, what I desire to secure by Letters Patent is:

1. A drive for a traverse mechanism of a textile machine, comprising a sprocket operatively connected to the traverse mechanism for applying a reciprocatory movement thereto, means including a fluid operated piston mechanically connected to said sprocket for rotating said sprocket, means for supplying fluid under pressure for moving said piston, and means, including a pneumatically operated valve, for controlling the flow of fluid to said piston.

2. A drive for a traverse mechanism of a textile machine, comprising a sprocket operatively connected to the traverse mechanism for applying a reciprocatory movement thereto, means including a fluid operated piston mechanically connected to said sprocket for rotating said sprocket, means for supplying fluid under pressure for moving said piston, means, including a pneumatically operated valve, for controlling the flow of fluid to said piston, said valve comprising a cylinder and a piston mounted therein for reciprocating relative thereto, and means operated by the movement of said first-mentioned piston for effecting movement of said second-mentioned piston.

3. A drive for a traverse mechanism of a textile machine, comprising a sprocket operatively connected to the traverse mechanism for applying a reciprocatory movement thereto, means including a double-acting oil cylinder and a piston mechanically connected to said sprocket and mounted for reciprocatory movement in said cylinder for rotating said sprocket, means for supplying oil under pressure to said cylinder for causing said piston to reciprocate therein, and means, including a pneumatically operated valve, for controlling the flow of oil to said cylinder.

4. A drive for a traverse mechanism of a textile machine, comprising a sprocket operatively connected to the traverse mechanism for applying a reciprocatory movement thereto, means in-

cluding a double-acting oil cylinder and a piston mechanically connected to said sprocket and mounted for reciprocatory movement in said cylinder for rotating said sprocket, means for supplying oil under pressure to said cylinder for causing said piston to reciprocate therein, and means for controlling the flow of oil to said cylinder, said flow controlling means comprising a cylinder, operatively connected to said first-mentioned cylinder, for initially receiving the oil, a piston in said second-mentioned cylinder and pneumatic means for operating said piston for selectively permitting the flow of oil from one cylinder to the other.

15 5. A drive for a traverse mechanism of a textile machine, comprising a sprocket operatively connected to the traverse mechanism for applying a reciprocatory movement thereto, means including a double-acting oil cylinder and a piston mechanically connected to said sprocket and mounted for reciprocatory movement in said cylinder for rotating said sprocket, means for supplying oil under pressure to said cylinder for causing said piston to reciprocate therein, and means for controlling the flow of oil to said cylinder, said flow controlling means comprising a cylinder, operatively connected to said first-mentioned cylinder, for initially receiving the oil, a piston in said second-mentioned cylinder for reciprocation therein, and pneumatic means for operating said piston for selectively permitting the flow of oil from one cylinder to the other.

20 6. A drive for a traverse mechanism of a textile machine, comprising a sprocket operatively connected to the traverse mechanism for applying a reciprocatory movement thereto, means including a double-acting oil cylinder and a piston mounted for reciprocatory movement therein for rotating said sprocket, means for supplying oil under pressure to said cylinder for causing said piston to reciprocate therein, and means for controlling the flow of oil to said cylinder, said flow controlling means comprising a cylinder, operatively connected to said first-mentioned cylinder, for initially receiving the oil, a piston in said second-mentioned cylinder for reciprocation therein, and pneumatic means including a valve operated by said first-mentioned piston for operating the piston in said second-mentioned cylinder for selectively permitting the flow of oil from one cylinder to the other.

25 7. A drive for a traverse mechanism of a textile machine, comprising a sprocket operatively connected to the traverse mechanism for applying a reciprocatory movement thereto, means including a double-acting oil cylinder and a piston mounted for reciprocatory movement therein for rotating said sprocket, means for supplying oil under pressure to said cylinder for causing said piston to reciprocate therein, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by said first-mentioned piston for operating the piston in said second-mentioned cylinder for selectively permitting the flow of oil from one cylinder to the other, and means for latching the latter piston at the end of each stroke thereof.

30 8. A drive for a traverse mechanism of a textile machine, comprising a sprocket operatively connected to the traverse mechanism for apply-

ing a reciprocatory movement thereto, means including a double-acting oil cylinder and a piston mounted for reciprocatory movement therein for rotating said sprocket, means for supplying oil under pressure to said cylinder for causing said piston to reciprocate therein, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by said first-mentioned piston for operating the piston in said second-mentioned cylinder for selectively permitting the flow of oil from one cylinder to the other and means for latching the latter piston at the end of each stroke thereof and for releasing said latching means at substantially the end of the stroke of said first-mentioned piston.

9. A drive for a traverse mechanism of a textile machine, comprising an eccentric sprocket operatively connected to the traverse mechanism for applying a uniformly accelerated rate of traverse to the reciprocating member thereof, means including a fluid operated piston for rotating said eccentric sprocket and means operated by said piston for superimposing a small traverse on said first-mentioned traverse.

10. A drive for a traverse mechanism of a textile machine, comprising a double-acting oil cylinder, a piston mounted for reciprocatory movement therein, a piston rod connected to said piston and extending through both ends of said cylinder, a sprocket operatively connected to each end of said piston rod and adapted to be rotated thereby simultaneously in opposite directions, a connection between each of said sprockets and the traverse mechanism whereby the rotation of said sprockets causes the reciprocation thereof, means for supplying oil under pressure to said cylinder for effecting movement of said piston and piston rod with respect to said cylinder, and means for controlling the flow of oil to said cylinder.

11. A drive for a traverse mechanism of a textile machine, comprising a double-acting oil cylinder, a piston mounted for reciprocatory movement therein, a piston rod connected to said piston and extending through both ends of said cylinder, a sprocket operatively connected to each end of said piston rod and adapted to be rotated thereby simultaneously in opposite directions, a connection between each of said sprockets and the traverse mechanism whereby the rotation of said sprockets causes the reciprocation thereof, means for supplying oil under pressure to said cylinder for effecting movement of said piston and piston rod with respect to said cylinder, means for controlling the flow of oil to said cylinder, said flow controlling means comprising a cylinder, operatively connected to said first-mentioned cylinder, for initially receiving the oil, a piston in said second-mentioned cylinder, and means for operating said piston for selectively permitting the flow of oil from one cylinder to the other.

12. A drive for a traverse mechanism of a textile machine, comprising a double-acting oil cylinder, a piston mounted for reciprocatory movement therein, a piston rod connected to said piston and extending through both ends of said cylinder, a sprocket operatively connected to each end of said piston rod and adapted to be rotated thereby simultaneously in opposite di-

rections, a connection between each of said sprockets and the traverse mechanism whereby the rotation of said sprockets causes the reciprocation thereof, means for supplying oil under pressure to said cylinder for effecting movement of said piston and piston rod with respect to said cylinder, means for controlling the flow of oil to said cylinder, said flow controlling means comprising a cylinder, operatively connected to said first-mentioned cylinder, for initially receiving the oil, a piston in said second-mentioned cylinder for reciprocation therein, and pneumatic means for operating said piston for selectively permitting the flow of oil from one cylinder to the other.

13. A drive for a traverse mechanism of a textile machine, comprising a double-acting oil cylinder, a piston mounted for reciprocatory movement therein, a piston rod connected to said piston and extending through both ends of said cylinder, a sprocket operatively connected to each end of said piston rod and adapted to be rotated thereby simultaneously in opposite directions, a connection between each of said sprockets and the traverse mechanism whereby the rotation of said sprockets causes the reciprocation thereof, means for supplying oil under pressure to said cylinder for effecting movement of said piston and piston rod with respect to said cylinder, means for controlling the flow of oil to said cylinder, said flow controlling means comprising a cylinder, operatively connected to said first-mentioned cylinder, for initially receiving the oil, a piston in said second-mentioned cylinder for reciprocation therein, and pneumatic means including a valve operated by said first-mentioned piston for operating the piston in said second-mentioned cylinder for selectively permitting the flow of oil from one cylinder to the other.

14. A drive for a traverse mechanism of a textile machine, comprising a double-acting oil cylinder, a piston mounted for reciprocatory movement therein, a piston rod connected to said piston and extending through both ends of said cylinder, a sprocket operatively connected to each end of said piston rod and adapted to be rotated thereby simultaneously in opposite directions, a connection between each of said sprockets and the traverse mechanism whereby the rotation of said sprockets causes the reciprocation thereof, means for supplying oil under pressure to said cylinder for effecting movement of said piston and piston rod with respect to said cylinder, means for controlling the flow of oil to said cylinder, said flow-controlling means comprising a cylinder, operatively connected to said first-mentioned cylinder, for initially receiving the oil, a piston in said second-mentioned cylinder for reciprocation therein, pneumatic means including a valve operated by said first-mentioned piston for operating the piston in said second-mentioned cylinder for selectively permitting the flow of oil from one cylinder to the other, and means for latching the latter piston at the end of each stroke thereof.

15. A drive for a traverse mechanism of a textile machine, comprising a double-acting oil cylinder, a piston mounted for reciprocatory movement therein, a piston rod connected to said piston and extending through both ends of said cylinder, a shaft operatively connected to each end of said piston rod, said shafts being adapted to be rotated by said piston rod simultaneously in opposite directions, a sprocket

mounted on each shaft, a connection between each of said sprockets and the traverse mechanism whereby the rotation of said sprockets by movement of said shafts causes the reciprocation thereof, means for supplying oil under pressure to said cylinder for effecting movement of said piston and said piston rod with respect to said cylinder, and means for controlling the flow of oil to said cylinder, said flow controlling means comprising a cylinder, operatively connected to said first-mentioned cylinder, for initially receiving the oil, a piston in said second-mentioned cylinder for reciprocation therein, a pneumatic means including a valve operated by the rotation of one of said shafts for operating the rotation of one of said shafts for operating the piston in said second-mentioned cylinder for selectively permitting the flow of oil from one cylinder to the other, means for latching the latter piston at the end of each stroke thereof, and means operated by the other of said shafts for releasing said latching means.

16. A drive for a traverse mechanism of a textile machine, comprising a double-acting oil cylinder, a piston mounted for reciprocatory movement therein, a piston rod connected to said piston and extending through both ends of said cylinder, a shaft operatively connected to each of said piston rod, said shafts being adapted to be rotated by said piston rod simultaneously in opposite directions, a sprocket mounted on each shaft, a connection between each of said sprockets and the traverse mechanism whereby the rotation of said sprockets by movement of said shafts causes the reciprocation thereof, means for supplying oil under pressure to said cylinder for effecting movement of said piston and said piston rod with respect to said cylinder, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by the rotation of one of said shafts for operating the piston in said second-mentioned cylinder for selectively permitting the flow of oil from one cylinder to the other, means including dogs on the piston in second-mentioned cylinder for latching said piston at the end of each stroke thereof, and means operated by the other of said shafts for releasing said latching.

17. A drive for a traverse mechanism of a textile machine, comprising a double-acting oil cylinder, a piston mounted for reciprocatory movement therein, a piston rod connected to said piston and extending through both ends of said cylinder, a shaft operatively connected to each end of said piston rod, said shafts being adapted to be rotated by said piston rod simultaneously in opposite directions, a sprocket mounted on each shaft, a connection between each of said sprockets and the traverse mechanism whereby the rotation of said sprockets by movement of said shafts causes the reciprocation thereof, means for supplying oil under pressure to said cylinder for effecting movement of said piston and said piston rod with respect to said cylinder, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by the rotation of one of said shafts for operating the piston in said second-mentioned cylinder for selectively permitting the flow of oil from one cylinder to the other, and means, including an eccentric bearing mounted on said rod and operated by said cam for superimposing a small traverse on said first-mentioned traverse.

cluding a valve operated by the rotation of one of said shafts for operating the piston in said second-mentioned cylinder for selectively permitting the flow of oil from one cylinder to the other, means including dogs on the piston in second-mentioned cylinder and latches cooperating with said dogs for latching said piston at the end of each stroke thereof and means, including a cam and rod cooperating with said cam operated by the other of said shafts for releasing said latches at predetermined times.

18. A drive for a traverse mechanism of a textile machine, comprising a double-acting oil cylinder, a piston mounted for reciprocatory movement therein, a piston rod connected to said piston and extending through both ends of said cylinder, a shaft operatively connected to each end of said piston rod, said shafts being adapted to be rotated by said piston rod simultaneously in opposite directions, an eccentric sprocket mounted on each shaft, a connection between each of said sprockets and the traverse mechanism whereby the rotation of said sprockets by movement of said shafts causes the reciprocating member of the traversing means to move at a uniformly accelerated rate of traverse, means for supplying oil under pressure to said cylinder for effecting movement of said piston and said piston rod with respect to said cylinder, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by the rotation of one of said shafts for operating the piston in said second-mentioned cylinder for selectively permitting the flow of oil from one cylinder to the other, and means on said rod and operated by said cam for superimposing a small traverse on said first-mentioned traverse.

19. A drive for a traverse mechanism of a textile machine, comprising a double-acting oil cylinder, a piston mounted for reciprocatory movement therein, a piston rod connected to said piston and extending through both ends of said cylinder, a shaft operatively connected to each end of said piston rod, said shafts being adapted to be rotated by said piston rod simultaneously in opposite directions, an eccentric sprocket mounted on each shaft, a connection between each of said sprockets and the traverse mechanism whereby the rotation of said sprockets by movement of said shafts causes the reciprocating member of the traversing means to move at a uniformly accelerated rate of traverse, means for supplying oil under pressure to said cylinder for effecting movement of said piston and said piston rod with respect to said cylinder, and means for controlling the flow of oil to said cylinder, said flow controlling means comprising a cylinder, operatively connected to said first-mentioned cylinder, for initially receiving the oil, a piston in said second-mentioned cylinder for reciprocation therein, pneumatic means including a valve operated by the rotation of one of said shafts for operating the piston in said second-mentioned cylinder for selectively permitting the flow of oil from one cylinder to the other, and means, including an eccentric bearing mounted on said rod and operated by said cam for superimposing a small traverse on said first-mentioned traverse.

Certificate of Correction

November 20, 1951

JOSEPH L. KILLORAN

It is hereby certified that error appears in the printed specification of the above numbered patent requiring correction as follows:

Column 4, line 8, after the syllable "inder" and before the period insert 28; column 8, line 36, for "cluding" read *including*; column 9, line 16, strike out "rotation of one of said shafts for operating the"; line 29, after "each" insert *end*;

and that the said Letters Patent should be read as corrected above, so that the same may conform to the record of the case in the Patent Office.

Signed and sealed this 4th day of March, A. D. 1952.
